UNITED STATES PATENT OFFICE.

CHARLES S. BATDORF, OF BROOKLYN, NEW YORK, ASSIGNOR TO AUTOMATIC COIN-WRAPPING MACHINE COMPANY, OF NEW YORK, N. Y., A CORPORATION OF NEW YORK.

COIN-HANDLING MACHINE.

1,130,245.

Specification of Letters Patent. Patented Mar. 2, 1915.

Application filed May 11, 1910. Serial No. 560,555.

To all whom it may concern:

Be it known that I, CHARLES S. BATDORF, a citizen of the United States, residing at Brooklyn, county of Kings, State of New York, have invented certain new and useful Improvements in Coin-Handling Machines, of which the following is a full, clear, and exact description.

My invention relates to coin handling machines of the type which is designed to assemble coins of different denominations in stacks, which stacks are subsequently wrapped in a suitable covering, the ends of which covering are crimped against the ends of the stack to secure the package. A machine of this type is illustrated in my Patent No. 998,834 of July 25, 1911, and the present application relates particularly to improvements in the adjustment of the wrapper crimping mechanism and the severing knife of the wrapper strip, whereby said parts may be readily adapted to operate upon wrappers of different lengths, and also sever the wrapper strip in lengths corresponding to the diameter of the stack to be wrapped.

With these objects in view, the invention consists in the construction and arrangement of parts, a preferred embodiment of which is illustrated in the accompanying drawings, in which—

Figure 1 is a plan view of so much of a coin handling machine of this type as is necessary to illustrate my invention. Fig. 2 is a rear view of the parts shown in Fig. 1. Fig. 3 is a vertical section on the line 3—3 Fig. 1, showing also wrapper supply support and feed rolls in conjunction with the severing knife, crimping fingers and wrapping rolls.

In the embodiment of my invention herein selected for illustration, 1 indicates the upper portion of the frame of a coin stacking and wrapping machine similar to that illustrated in my patent above referred to, upon which are mounted wrapping rolls 2 and 3 carried by suitable arms 4 and 5 respectively, which in turn are mounted upon supporting brackets 6.

7 indicates a third or forward wrapping roll, which co-operates with the rolls 2 and 3 to perform the wrapping operation, and 8 indicates one of the pair of gripper arms by which a stack of coins is transferred from

the stacking mechanism to the wrapping 55 rolls.

9 indicates the wrapper supply support, which is adjustably mounted upon a transverse frame bar 10, in order that said support may be positioned in accordance with 60 the width of the wrapping strip employed.

11 and 11' indicate feed rolls between which the wrapper strip is fed to the severing knife 12. The latter is mounted upon the forward end of the rocking frame 13 65 supported upon a shaft 14 at the rear of the machine, said frame being weighted at 15 to balance the weight of the forward portion thereof and the parts carried thereby.

16 indicates a wrapper strip guide which 70 overlies the severing knife and serves to maintain the wrapper strip in close proximity thereto.

As will be seen from an inspection of Fig. 1, the cutting edge of the knife is angular in 75 outline, to facilitate the severing operation of the strip.

Machines of the type here selected are intended to operate upon coins of different denominations and also upon different quantities of each coin. It will be obvious, therefore, that the stacks of coin to be wrapped will vary, both in length and in diameter. Consequently it is necessary to provide 80 wrapper strips of different widths, and for 85 the sake of economy to sever the strips into different lengths in order that the stacks of different diameter may receive substantially the same number of turns of the wrapper. It is necessary, therefore, that the crimping 90 mechanism shall be adjustable to operate upon these different lengths of stacks, and that the severing knife shall also be adjusted to sever the strips into different 95 lengths. For the sake of simplicity of construction, moreover, it is desirable that only one of the crimpler fingers shall be made adjustable, while the other remains fixed in lateral position. It is, therefore, necessary in order that the severing knife shall always 100 be centered with reference to the crimpler fingers and with reference to the length of the stack, that said knife may be adjusted laterally simultaneously with the adjustment toward and from each other of the 105 crimpler fingers. To accomplish these objects, the following constructions have been devised. As indicated in Fig. 1, the crimpler

fingers 18 are mounted upon blocks 19 slidably supported upon a transverse bar 20, Fig. 1, the latter being supported at either end in rock arms 21, Fig. 3, pivoted at 22 to 5 adjustable arms 23, which in turn are carried by pins 24 and 25 projecting outwardly from slides (not shown) on the wrapping roll supporting brackets 6, as fully set forth in my copending application Serial No. 10 554,642, filed April 11th, 1910. Each of the crimpler finger supporting blocks 19 is provided with a depending fork 26, Fig. 3, which is engaged by a forwardly projecting finger 27, mounted in the hub 28, which in 15 turn is slidably carried upon a transverse frame bar 29. Upon the rear of the hub 28 is mounted a cam roll 30 arranged to engage a rotary cam 31 on the transverse cam shaft 32. The cam 31 on the right hand side, 20 as viewed from the rear, Fig. 2, is fixed against lateral movement, whereas the cam 31 on the left hand side, as viewed in said figure, is mounted to slide laterally upon the cam shaft 32, and is splined thereto by 25 the feather 33. The rolls 30 are held in engagement with the cams 31 by means of springs 34 mounted upon the transverse finger carrying bar 29.

In order to adjust the cam on the left, as 30 viewed in Fig. 2, laterally, the hub thereof is provided with an annular groove engaged by an adjusting finger 35 secured to a longitudinally sliding adjusting bar 36 suitably supported in the machine frame. The 35 outer end of said bar is provided with a lever 37 pivoted at 38 on the machine frame, said lever having at its opposite end a handle 39 for manual operation. A suitable dial or scale may be located opposite the 40 lever 37 bearing markings whereby the proper adjustments may be determined. It will be clear from an inspection of the drawings that adjustment of cam 31 will simultaneously effect adjustment of the 45 crimpler finger whose cam roll 30 is engaged thereby. In order to adjust the severing knife laterally simultaneously with the adjustment of the crimpler finger just described, so that said knife may always be 50 centered with respect to said crimpler fingers, the frame of said knife is mounted to slide laterally upon the supporting bar 14, and the hub 13' of said frame is provided with a stud 40, which is engaged by a lever 55 41 pivoted at 42 upon a transverse frame bar 43, the lower end of said lever being forked at 44 to engage the stud 45 fixed upon the adjusting rod 36 just described. The arms of the lever 41 are so 60 proportioned that the knife will always be centered with respect to the crimpler fingers in all positions of lateral adjustment of the latter.

In order to provide for severing of wrap- 65 per strips in lengths according to the dia-

ter of the stack to be wrapped, it is necessary that the knife be capable of adjustment toward and from the wrapping roll. For this purpose the hub of the knife frame is splined to its supporting shaft 14, and although capable of sliding movement thereon, is fixed against rotation independently thereof. The shaft 14 furthermore is provided with a lever arm 46 fixed thereto, to the end of which is pivoted an adjusting rod 47 extending to the front of the machine and there pivoted to a crank arm 48 on the short shaft 49 supported by the machine frame, said shaft being provided with an adjusting handle 50, which likewise may cooperate with a dial or scale to determine the necessary adjustment of the knife. It will be clear from the above description that by manipulating the adjusting handle 50 the severing knife may be moved toward or from the feed rolls at will, thereby providing for the severing of wrapper strips of different lengths.

While I have herein described a particular embodiment of my invention, the same may be altered in detail and relative arrangement of parts within the scope of the appended claims.

What I claim is:

1. In a coin handling machine, the combination with coin wrapping mechanism of a pair of crimpler fingers for crimping the ends of the wrapper on the opposite ends of the stack of articles to be wrapped, a wrapper supply mechanism and a severing knife for severing the required length of wrapper from said supply, and means for adjusting said crimpler fingers to accommodate stacks of articles of different lengths and to simultaneously center said knife with respect to said fingers.

2. In a coin handling machine, the combination with coin wrapping mechanism, of a pair of crimpler fingers for crimping the wrapper upon the ends of the stack of articles to be wrapped, a wrapper supply mechanism, a severing knife therefor, and means for simultaneously adjusting said fingers to accommodate stacks of articles of different lengths and for centering said knife with respect to said fingers in all positions of adjustment, and independent means for adjusting said knife toward and from said wrapping mechanism to sever wrappers of different lengths according to the diameter of the stack to be wrapped.

3. In a coin handling machine, the combination with coin wrapping mechanism, of crimping mechanism for crimping the ends of the wrapper on the opposite ends of a stack of articles to be wrapped, a wrapper supply mechanism and means for severing the required quantity of wrapping material from the wrapper supply and means for co-ordinately adjusting the crimping mecha-

nism and severing mechanism to accommodate stacks of articles of different lengths and to adjust the severing mechanism in accordance with the adjustment of the crimping mechanism.

4. In a coin handling machine, the combination with a coin wrapping mechanism, of crimping mechanism for crimping the ends of a wrapper on the opposite ends of a stack of articles to be wrapped, a wrapper supply mechanism, and means for severing the required amount of wrapping material from

the wrapper supply and means for adjusting the crimping mechanism to accommodate stacks of articles of different lengths 15 and means to adjust the severing mechanism to vary the length of the wrapping material supplied in accordance with the diameter of the stack of articles to be wrapped.

CHARLES S. BATDORF.
